HOLDUP FOR LUG STRAPS

Wingo Herron, Augusta, Ga.

Application September 27, 1944, Serial No. 556,045

1 Claim. (Cl. 139—154)

The invention relates to a loom attachment, and more especially to a hold-up device for a lug strap of a loom.

The primary object of the invention is the provision of a device of this character, wherein the lug stick and the picker staff or stick are held loop connected with each other, and within the lug strap is removably fitted the hold-up, which is constructed from super-imposed plies of fibrous material, one being made from leather and the others of fabric bonded with rubber composition, these being die cut to shape and riveted to the leather for a unitary set-up.

Another object of the invention is the provision of a device of this character, wherein it will not cut through the lug straps, and are assured of maximum wearing quality, withstanding strains and stresses in the working of the picker staff or stick and without mutilating activity on the latter in the operation of the loom.

A further object of the invention is the provision of a device of this character, which is simple in construction, thoroughly reliable and efficient in operation, strong, durable, readily and easily applied in place and removed when required, adapted for loose interfitting with the lug strap, and inexpensive to manufacture and install.

With these and other objects in view, the invention consists in the features of construction, combination and arrangement of parts as will be hereinafter more fully described, illustrated in the accompanying drawing, which shows the preferred embodiment of the invention and pointed out in the claims hereunto appended.

In the accompanying drawing:

Figure 1 is a fragmentary side view of a loom frame having the lug stick, picker stick and lug strap with the device constructed in accordance with the invention applied to the latter, and the picker stick in contact therewith.

Figure 2 is a sectional view taken on the line 2—2 of Figure 3 looking in the direction of the arrows.

Figure 3 is a sectional view taken on the line 3—3 of Figure 2 looking in the direction of the arrows.

Figure 4 is a perspective view of the lug strap with the device in position therein.

Similar reference characters indicate corre-

sponding parts throughout the several views in the drawing.

Referring to the drawing in detail, A designates generally a portion of the loom frame, having arranged therewith the lug strap 10 loosely connected at 11 to the lug stick 12, and within this strap is located the picker staff or stick 13, as usual, which is loosely attached to the frame A for operation in the ordinary well known manner.

Within the lug strap 10 is hung the hold-up device B, which comprises a frontal section or plies 14, preferably made of a piece of leather having a determined thickness, and backing ply or section 15, preferably made from fabric bonded with a rubber composition, which is die cut to shape and then vulcanized in a mold. These sections or plies 14 and 15, after the cutting and shaping of the former, are brought together in 10 matched relation to one another, with a centrally located longitudinally disposed inherently springy steel strip 16 interposed therebetween, and riveted, as at 17 to each other, best seen in Figures 2, 3 and 4 of the drawing.

The hold-up consists of a head 18, a bottom portion 19, and an intermediate body area or portion 20, respectively, and in opposite sides of the latter are inwardly directed notches 21 for the loose accommodation of the side stretches of the lug strap 10, whereby the hold-up will be interfitting thereto, as best seen in Figure 4 of the drawing, for hold-up action against the staff or stick 13, which can be readily noted in Figure 1.

The springy leaf or strip 16 is maintained 25 against displacement by certain of the rivets 17 which anchor it in place, as will be apparent from Figure 3 of the drawing, as Figure 2 thereof.

What is claimed is:

A hold-up for a lug strap of a loom, comprising 30 a fibrous frontal section, a rubber vulcanized fabric backing section thereto, a springy metal strip between said sections at the medial portion thereof and extending from the top of said sections to the bottom thereof, means uniting the sections and strip together, a head formation to the sections, a bottom portion formed on said sections and an intermediate body area therebetween and having opposed notches for loosely receiving side stretches of said lug strap.

WINGO HERRON.
